Fig. 2

Diagram illustrating a gasoline dispensing system. The system includes a GASOLINE tank (10), a WATER tank (11), a CHEMICAL tank (12), and a PURIFIED GASOLINE outlet (26). The GASOLINE tank (10) is connected to the WATER tank (11) via a line (10') with a valve (11a). A PROPORTIONING DEVICE (10a) is located on the line between the tanks. The system then splits into two parallel lines. The top line contains a PROPORTIONING DEVICE (13a) and a VENT (16). The bottom line contains a PROPORTIONING DEVICE (13b) and a VENT (17). Both lines converge into a central section. The central section contains a DISPERSION OF GASOLINE IN WATER unit (14, 15) and a HEAVY dispersion unit (18). Arrows indicate the flow of liquid from the tanks through the proportioning devices and dispersion units. The system then leads to a CENTRIFUGE SEPARATOR (25) and finally to a PURIFIED GASOLINE outlet (26). Various valves (12a, 21, 22, 23, 24, 26) and a SURGE TANK (23) are also shown.

METHOD OF REFINING HYDROCARBON LIQUIDS

Michele Bonotto, Princeton, N. J., assignor to
Dorothy Di Frasso, Beverly Hills, Calif.

Application October 29, 1941, Serial No. 416,939

3 Claims. (Cl. 196—41)

This invention relates to improvements in processes for refining hydrocarbon liquids used for motor fuel or solvent, such as gasoline, naphtha and the like, and utilizing the refined liquid.

Certain grades of motor fuels now on the market contain more or less soluble gums, resins and other heavier undesirable components and it has been found that these motor fuels, when mixed with air in conventional proportions and ignited in the cylinder of an internal combustion engine, contribute to the production, under conventional conditions, of what has come to be known as a "fuel knock" in contradistinction to a "mechanical knock."

Also, because of incomplete combustion, these gums, resins and heavier constituents produce a sediment and incrustation in and on the walls of the explosion chamber and other parts of an internal combustion engine and also causes smoke in the exhaust pipe.

One of the objects of this invention is to produce a hydrocarbon liquid from which the soluble gums, resins and other heavier undesirable components have been rendered insoluble and removed and thus to provide a motor fuel or solvent having a low content of such components.

Another object of my invention is to produce, at a relatively low cost, a hydrocarbon liquid that will be free from the undesirable ingredients hereinabove referred to to such an extent as to provide a motor fuel that, when mixed with air in any conventional proportion and ignited in the cylinder of internal combustion engine, will be completely burned without smoke and without leaving an insulating film, coating or deposit in or on the combustion chambers or cylinders, valves and valve stems, or spark plug points.

Another object of my invention is to produce such a treated hydrocarbon liquid that will have increased susceptibility to tetra ethyl lead over the untreated liquid so that by the addition of tetra ethyl lead fluid to my treated hydrocarbon liquid, a motor fuel may be produced of higher octane rating than would be possible with the same liquid without treatment.

Another object of my invention is to provide an economical process for the continuous treatment of hydrocarbon liquids of the type hereinabove specified for the purpose of removing gums, resins or other heavier undesirable components and thus to refine or purify such hydrocarbon liquids.

Another object of my invention is to provide a process that may be carried out at room tem-

peratures in simple and inexpensive apparatus.

Another object of my invention is to finely divide a quantity of gasoline to be treated into small droplets to enable treatment of the same with small amounts of suitable chemicals by providing better contact in the presence of water, between the hydrocarbon droplets or particles and the treating chemicals, and in the preferred embodiment of my invention, I utilize a mixture comprising a high dispersion of water in gasoline or an emulsion of water and gasoline preferably in the proportion of three parts of gasoline to one part of water.

Another object of my invention is to subject 15 the highly dispersed or divided gasoline droplets or particles to treatment by two groups of chemicals, the first group comprising hydroxides of heavy metals such as lead, iron, copper, zinc, silver, nickel and also aluminum hydroxide, and 20 the second group comprising strong alkalies such as sodium, potassium, barium or ammonium hydroxides and I have found that an efficient and economical method of utilizing the metallic hydroxides is to employ the same in solution in 25 strong alkalies, such as sodium, potassium, barium or ammonium hydroxides, and where it is found more economical, I dissolve the metallic oxide in a solution of the hydroxide of the strong alkali.

Another object of my invention is to utilize 30 a process in which the gums and other heavier components may be treated in the presence of water with a precipitating agent, such as hydroxides of any of the metals of the first group 35 which are soluble or may be caused to be soluble in water, or which are capable of being suspended in water.

Another object of my invention is to provide 40 a method in which a metallic hydroxide of the first group is associated with one or more of the above specified strong alkalies in order to produce a higher percentage of precipitation of the soluble gums, resins and like heavier components at room temperature and to produce a 45 precipitate which I believe to be a saponified product comprising a complex of soaps.

Another object of my invention is to provide 50 a method in which two or more metallic hydroxides of the first group are associated with one of the above specified strong alkalies to produce, as hereinabove specified, a higher percentage of precipitation and what I believe to be a mixture of soaps.

Still another object of my invention is to provide 55 a motor fuel that has been subjected to

the purifying action of metallic hydroxide and to the action of strong alkaline hydroxides.

With these and other objects in view the invention comprises the combination of members and arrangement of parts so combined as to coact and co-operate with each other in the performance of the functions and the accomplishment of the results herein contemplated, and comprises in one of its adaptations the species or preferred form illustrated in the accompanying drawings, in which:

Figs. 1, 1^a and 1^b are diagrammatic views of a batch system apparatus capable of carrying out my invention;

Fig. 2 is another diagrammatic view of my preferred form of apparatus for carrying out my invention as a continuous system and comprising horizontally disposed units; and

Fig. 3 is a similar diagrammatic view showing a modified form of continuous system employing vertically disposed units.

Referring now to these drawings and more particularly to Fig. 1 which illustrates a form of apparatus suitable for carrying out my invention in accordance with a batch system and when I employ as the treating ingredients lead hydroxide and sodium hydroxide, I may proceed as follows: First I dissolve eighty (80) grams of sodium hydroxide in 300 cubic centimeters of water in a separate container; then I heat this solution in said container to the boiling point and add, little by little, twenty-five (25) grams of lead oxide (PbO) and agitate the combined ingredients until the lead oxide is fully dissolved. To this solution, I then add in said container 1000 cubic centimeters of water. The gasoline to be treated is introduced into a mixing tank 1 which, in the particular embodiment heretofore used, was twenty (20) inches in diameter and four feet high and was provided with a centrally disposed shaft 2 having mounted thereon within the tank agitating paddles 3. The said shaft 2 is suitably mounted in said tank and, as shown, is mounted at its bottom portion in a bearing 4 supported at the bottom of the tank and extends through a stuffing box 5 supported in the cover 1' of the tank, the said shaft being also supported outside the tank above the cover in a bearing 6 elevated from the cover of the tank by a spider 7. The shaft 2 may be revolved by any suitable power, and, as shown, is provided with a motor 8. The gasoline is introduced into the tank through any suitable pipe or opening 10 and I then add to said gasoline, water in a quantity preferably amounting to one-fourth (1/4) of the volume of gasoline, this proportion of water and gasoline being economical, though I may, if desired, use any suitable lesser or greater proportion of water. The agitating paddles are then revolved through the shaft 2 at approximately 600 R. P. M. and I find that after 30 to 45 seconds the dispersion of the water in gasoline has reached a point sufficient to permit continuation of the treatment. I then add to the highly dispersed water in gasoline, a quantity of the prepared solution described above amounting to from two or four cubic centimeters per gallon of gasoline, and this prepared solution is introduced by drops or spraying to the mixing drum during the running and agitation of the dispersed liquids therein. After a period of from 15 to 30 seconds, I notice that a thickening of the dispersed liquids or emulsion has taken place and the process is completed. I then stop the machine and the dispersion or emulsion on such

stoppage separates into three layers, the bottom layer being water, the middle layer comprising a flocculent precipitate and the top layer comprising purified gasoline. By any conventional means I may then decant or remove the gasoline or, if desired, the mixture may be conducted to a centrifuging machine and the purified gasoline may be thus separated from the water and flocculent precipitate.

10 In Fig. 2 which illustrates a preferred form of apparatus for carrying out my invention as a continuous system, I have shown the supply of gasoline to be treated stored in a tank 10, the water to be used is stored in a tank 11 and the prepared chemical solution described above in a tank 12, while the treating apparatus comprises a horizontally-disposed cylindrical drum 13, provided with an axially disposed shaft 14 having mounted thereon paddles 15 revolved by a motor 16. The shaft is, of course, suitably supported in bearings and provided with a conventional stuffing box. The tank 13 has a gasoline inlet 13' and water inlet 13^a arranged at the forward end of the tank and is provided at its rear end with a baffle 16. The gasoline from tank 10 is fed through pipe 10' to the treating drum and the water is fed through pipe 11' from the water tank 11, these liquids being so fed preferably in proportion of one fourth (1/4) of a unit of water to three-fourths (3/4) of a unit of gasoline, it being understood that suitable proportioning devices 10^a and 11^a are provided in the pipes 10' and 11' to enable proper proportions of gasoline and water to be supplied to the drum 13. In this embodiment of the invention, the motor 16 continuously revolves the shaft 14 and the water and gasoline are immediately mixed in proper dispersion or emulsion, the time of 30 to 45 seconds or duration of agitation required to produce this emulsion is occupied by providing a drum of suitable capacity and length and utilizing a baffle of suitable height as well as by providing a proper number of paddles or other agitating devices in relation to the capacity of the drum. In this embodiment, the water in gasoline is highly dispersed and such highly dispersed immiscible liquids pass over the baffle 16 and are then conducted through a rear chamber 13^b and through 25 a pipe or conduit 17 to the treating drum 18. A pipe 12' provided with a suitable proportioning device 12^a, and leading from the chemical storage tank 12 is connected with this treating drum at its forward end to conduct a properly proportioned supply of chemicals thereto. The dispersed solution of water in gasoline is thus caused to mingle at this point with a solution of the chemicals which are preferably sprayed by a nozzle 12^b into said treating drum. The treating 30 drum 18 is also provided with a shaft 19 having mounted thereon paddles 20 and being revolved by a motor 21. In the tank 18, the chemicals are thoroughly mixed with the dispersion of water in gasoline and within 15 to 30 seconds after the addition of the chemicals hereinabove specified there occurs a thickening of the emulsion hereinabove referred to in regard to the batch system. The continuous revolution of the shaft 19, however, carries the thickened liquid over the baffle 35 21 mounted at the rear end of the drum. The thickened emulsion thus drops through the rear compartment 18' and it is then conducted by pipe 22 into a surge tank 23 from which it is then conducted by conduit 24 to a centrifuging machine 40 25 in which the purified gasoline is separated

from the water and passes out from a conduit 26 while the water and flocculent material passes out through the conduit 27. The flocculent material may then be further separated from the water by settling or by a second centrifuging operation. This completes the process. In case a metallic hydroxide is used alone, as hereinabove suggested, this metallic hydroxide may be added in the form of a spray to the liquid in the second drum in the same manner as the prepared solution referred to, or said metallic hydroxide may, if desired, be added in powdered form through a suitable rotary powder-feeding valve.

It will be seen that this process is entirely continuous and can be carried out in a highly economical manner. In the preferred proportioning of the gasoline and water and chemicals, I utilize three gallons of gasoline per minute to one gallon of water per minute, and during this time I add to the dispersed gasoline and water a quantity amounting preferably to nine (9) cubic centimeters per minute of the solution hereinabove specified in the description of my batch system. It will be understood that the dispersion or emulsion of gasoline causes the same to be finely subdivided and presents larger contact surface for treatment by the chemical.

In Fig. 3 I have shown a modified form of a continuous system capable of carrying out my invention with vertically disposed units. In this apparatus, I have shown a gasoline storage tank 30 for the gasoline to be treated, a storage tank 31 for the water to be used in the process and a storage tank 32 for the storage of the prepared chemical solution. The mixing apparatus comprises vertically-disposed tanks provided with mixing devices. As illustrated, a vertically-disposed cylindrical tank 33 is provided with an axially-disposed shaft 33^e having mounted thereon paddles 33^f which are revolved by a motor 36 through a medium of beveled gears 36'. The shaft is suitably supported at the bottom of the tank 33 in conventional bearings 33' and passes through a conventional stuffing box 33^a mounted at the top of said tank. A gasoline inlet 33^b and a water inlet 33^c are arranged at the bottom of the tank and its upper end has an outlet 33^d for the mixed and dispersed liquids. In carrying out my process, the gasoline from the tank 30 is fed through the pipe 30' to the treating tank 33 and water is fed from the water storage tank 31 through the pipe 31' to said treating tank, the liquids being so fed preferably in the proportions of one-quarter ($\frac{1}{4}$) of a unit of water and three-quarters ($\frac{3}{4}$) of a unit of gasoline, it being understood that suitable proportioning devices 30^a, 31^a are provided in the pipes 30', 31' to enable proper proportions of gasoline and water to be supplied to the tank 33. In this apparatus, the motor 36 continuously revolves the shaft 33^e and the water and gasoline are immediately mixed in proper dispersion or emulsion, the time of 30 to 45 seconds, which is the preferred duration of agitation required to produce this proper dispersion or emulsion being occupied by providing a tank of suitable capacity and height with a proper number of paddles or other agitating devices in relation to the capacity and height of the tank. In said apparatus, the water in gasoline is highly dispersed, and such highly dispersed immiscible liquids pass through the outlet 33^d and are conducted by pipe 34 through a dispersion inlet 35 located adjacent to the bottom of a tank 35. In the instant apparatus, the wall of the tank be-

tween the bottom thereof and the outlet opening 33^d takes the place of the baffle 16 of Fig. 2. The pipe 34 is provided with a suitable cut-off valve 34' and in the said apparatus shown, a by-pass 5 conduit 34^a is connected at one end with the bottom of the tank 33 and at its other end is connected to the pipe 34 which also is provided with a conventional cut-off valve 34^b. In the apparatus illustrated, as the dispersed liquids are fed 10 into the tank 35 through the outlet 35' adjacent to the bottom thereof, a supply of chemical is sprayed through the nozzle 37 arranged at substantially the same level and mixes with the dispersed liquids as they rise in the tank 35, it being 15 understood that the pipe 32' which conducts the chemicals from the chemical storage tank 32 to the treating tank 35 is provided with a proportioning device 32^a and thus feeds chemicals in proper proportion to the nozzle 37 under a suitable pressure to spray the same into the tank 35. Said conduit or pipe 32' also is provided, as 20 shown, with a usual or conventional cut-off valve 32^b. The dispersed solution of gasoline and water is thus caused to mingle and to be partially 25 mixed at the lower portion of the tank with the solution of the chemicals conducted through said pipe 32 and sprayed, as aforesaid, by the nozzle 37 into said treating tank and is preferably further and more intimately mixed by a suitable 30 mixing means as the combined dispersion and chemicals rise in said tank. For this purpose, the treating tank 35 is also provided with a shaft 38 having mounted thereon paddles 39 revolved by a motor 40 through the beveled gears 40'. 35 During the mixing operation in the tank 35, and within 15 to 30 seconds after addition to the dispersion of water in gasoline of the chemicals hereinabove specified, there occurs a thickening of dispersion in the same manner as hereinabove 40 referred to. Continuous revolution of the shaft 38 keeps this mixture and the thickened portions thereof in suspension, and the thickened mixture is carried upwardly until it finally reaches the outlet 41, and is then conducted through the pipe 45 or conduit 42 to a surge tank and centrifugal separator (not shown) such as hereinabove described in relation to Fig. 2. As illustrated, the tank 35 is provided with a by-pass 43 connected 50 at one end to the bottom of said tank 35 and at the other end with the pipe 42 and said tank 35 is also preferably provided with a drain pipe 44 having a conventional cut-off valve 44'.

In the centrifuging machine referred to, the purified gasoline is separated from the water and 55 passes out through one conduit while the water and flocculent material pass out through another. The flocculent material may then, as aforesaid, be separated from the water by a second centrifuging operation, if desired. This completes 60 the process. In case a metallic hydroxide is used alone, as hereinabove suggested, such metallic hydroxide may be added in the form of a spray to the liquids in the tank 35 in the same manner as the prepared solution referred to or said metallic hydroxide may, if desired, be added in powdered form through a suitable rotary powder-feeding valve.

In said Fig. 3, I have shown the tanks 33 and 35 connected by pipes 45 and 46 respectively to 70 reflux condensers 47 and 48 of conventional type.

In other respects this embodiment is similar to that shown in Fig. 2.

Having described my invention, I claim:

1. A method of refining and utilizing hydro- 75 carbon liquids containing soluble gums, resins

and heavier components consisting in providing a dispersion of such hydrocarbon liquid in water, then treating the dispersed liquid hydrocarbon with a solution of a metallic hydroxide in an aqueous solution of a strong alkali adapted to render the gums, resins and heavier components insoluble in said liquid hydrocarbon, and then separating such insoluble components and water from the hydrocarbon liquid.

2. A method of refining and utilizing hydrocarbon liquids containing soluble gums, resins and heavier components consisting in providing a dispersion of such hydrocarbon liquid in water, then treating the dispersed liquid hydrocarbon with a lead oxide in solution in a strong alkali adapted to render the gums, resins and

heavier components insoluble in said liquid hydrocarbon, and then separating such insoluble components and water from the hydrocarbon liquid.

- 5 3. A method of refining and utilizing hydrocarbon liquids containing soluble gums, resins and heavier components consisting in providing a dispersion of such hydrocarbon liquid in water, then treating the dispersed liquid hydrocarbon
- 10 with a lead hydroxide in solution in a strong alkali adapted to render the gums, resins and heavier components insoluble in said liquid hydrocarbon, and then separating such insoluble components and water from the hydrocarbon
- 15 liquid.

MICHELE BONOTTO.
